Primary Examiner — Katherine Glennon*Assistant Examiner* — Yuan Yuan(74) *Attorney, Agent, or Firm* — Fish & Richardson P.C.(57) **CLAIM**

The ornamental design for a turning toy, as shown and described.

DESCRIPTION

FIG. 1 is a first perspective view of our turning toy;
FIG. 2 is a second perspective view thereof;
FIG. 3 is a side view thereof;
FIG. 4 is a top view thereof;
FIG. 5 is a bottom view thereof; and,
FIG. 6 is a cross sectional view thereof, taken in a plane
containing a vertical axis through its center.
The design is axisymmetric about a vertical axis through its
center.
